UNITED STATES PATENT OFFICE.

THEODORE MILLER, OF NEW YORK, N. Y.

MANICURE IMPLEMENT.

No. 893,004.

Specification of Letters Patent.

Patented July 14, 1908.

Application filed November 8, 1907. Serial No. 401,230.

To all whom it may concern:

Be it known that I, THEODORE MILLER, a citizen of the United States, residing at New York city, Manhattan, county and State of 5 New York, have invented new and useful Improvements in Manicure Implements, of which the following is a specification.

This invention relates to a manicure implement which is of simple construction and 10 is adapted to thoroughly polish the entire surface of the nails without causing pain or injuring the cuticle.

In the accompanying drawing: Figure 1 is a face view of my improved manicure implement; Fig. 2 a cross section thereof, and Fig. 15 3 a perspective view of the implement showing it in use.

The manicure implement consists of two parts, viz:—a flexible plate 10 constituting a 20 handle, and a soft buffer 11 secured to said plate and projecting beyond the edge thereof. Plate 10 is of oblong shape and is preferably composed of cardboard having a sanded facing. Buffer 11, composed of 25 chamois skin or similar material, is glued to the back of plate 10 and projects uniformly beyond the edge thereof, so as to form a yielding flange 12 surrounding the plate.

In use, the device is grasped by plate 10 30 and is bent to conform to the bulge of the nail to be manicured. As the buffer is now passed over the nail it will neatly polish the

entire surface thereof. During this manipulation the flexible flange 12 will reach the inner edges of the nail, but will be deflected to 35 clear the cuticle, so as in no way to injure the same or cause pain. The sanded facing of plate 10 is designed to smoothen the outer edge of the polished nail. The device can be produced at little cost, and when worn or 40 soiled may be thrown away, so that cleanliness is invited.

I claim:

1. A manicure implement comprising two strips of material secured together with their 45 opposing surfaces lying in contact, one of said strips being composed of relatively hard resilient material and the other of relatively soft pliable material, and having its edges disposed outside those of the first strip. 50

2. A manicure implement comprising an elongated strip of relatively hard, resilient material having rounded end portions, and a strip of relatively soft, pliable material secured to said first-mentioned strip and projecting uniformly beyond the edge thereof to 55 form a surrounding, yielding flange.

Signed by me at New York city, (Manhattan,) N. Y., this 7th day of November, 1907.

THEODORE MILLER.
